CLAIM

The ornamental design for an apparatus for preparing and serving beverages, as shown and described.

DESCRIPTION

The patent or application file contains at least one drawing executed in color. Copies of this patent or patent application publication with color drawing(s) will be provided by the Office upon request and payment of the necessary fee.

FIG. 1 is a right front perspective view of an apparatus for preparing and serving beverages embodying our design;

FIG. 2 is a front view thereof;

FIG. 3 is a back view thereof;

FIG. 4 is a left end view thereof;

FIG. 5 is a right end view thereof;

FIG. 6 is a top view thereof;

FIG. 7 is a bottom view thereof;

FIG. 8 is left front perspective view thereof;

FIG. 9 is a left rear perspective view thereof;

FIG. 10 is a right rear perspective view thereof;

FIG. 11 is a right front perspective view of an apparatus for preparing and serving beverages embodying our design;

FIG. 12 is a front view thereof;

FIG. 13 is a back view thereof;

FIG. 14 is a left end view thereof;

FIG. 15 is a right end view thereof;

FIG. 16 is a top view thereof;

FIG. 17 is a bottom view thereof;

FIG. 18 is left front perspective view thereof;

FIG. 19 is a left rear perspective view thereof; and,

FIG. 20 is a right rear perspective view thereof.
